The ornamental design for a vaporizer power unit, as shown and described.

DESCRIPTION

FIG. 1 is a front perspective view of a first embodiment for a vaporizer power unit showing our new design;

FIG. 2 is a left side view thereof;

FIG. 3 is a front view thereof;

FIG. 4 is a right side view thereof;

FIG. 5 is a rear view thereof;

FIG. 6 is a top view thereof; and,

FIG. 7 is a bottom view thereof.

In FIG. 7 the evenly spaced broken line and the dash-dot-dash broken lines adjacent to the shaded regions in the drawings represent boundaries of the claimed design and form no part thereof. The remainder of the dash-dot-dash lines in the drawings represents aspects of the vaporizer power unit that form no part of the claimed design.
